MAGAZINE FOR AUTOMATIC FIREARMS

Hanns Lippert and Otto Schälkli, Zurich, Switzerland, assignors to Verwaltungsgesellschaft der Werkzeugmaschinenfabrik Oerlikon, Zurich-Oerlikon, Switzerland

Application March 18, 1944, Serial No. 527,045
In Switzerland March 19, 1943

3 Claims. (Cl. 42—50)

1

In automatic fire-arms the cartridges are placed in a magazine mounted above the breech block. The breech block on its forward travel introduces each time one cartridge into the cartridge chamber, and under the action of the spring fitted in the magazine the next cartridge is brought to the magazine outlet. The breech block on its forward travel which has to introduce a cartridge into the cartridge chamber now first imparts to the cartridge a short blow since the impact on the stationary cartridge takes place at a certain velocity. It may now occur that under the effect of the blow the cartridge acquires a velocity exceeding the velocity of the breech block on its forward travel, the consequence being that the cartridge to be introduced into the cartridge chamber drops in front of the extractor claw fitted on the breech block. As a result, after the firing of the cartridge the empty cartridge case is not extracted out of the cartridge chamber. This is naturally connected with troubles which should be avoided at all costs in automatic fire-arms.

The object of the present invention is to select for the magazine outlet a design eliminating the possibility for the cartridge to drop in front of the extractor claw under the effect of the blow imparted to it by the breech block on its forward travel.

According to the present invention this object is secured by providing the front ends of the guiding ledges fitted at the magazine outlet for the cartridge to be fed—with two projections facing each other and encompassing the cartridge case. The diameter of these projections is greater than the diameter of the cartridge case at its front end, so that the cartridge is able to glide on the guiding ledges; on the other hand it is smaller than the rear part of the tapered cartridge case. As a result, the cartridge case impelled forward by the breech block on its forward travel is clamped between the two projections, and can only be forced out of the guiding lips by the elastic widening of the magazine bottom. The guiding ledges facing each other are formed complementary to the shape of the cartridge and suitably encompass it above the middle axis so as to make it impossible for the cartridge to escape upwards whilst the breech block is impelling it forward.

The attached drawing shows in Figs. 1—4 details of the subject of the invention.

Figure 1 is a longitudinal vertical section of the outlet portion of a magazine embodying the present invention;

Figure 2 is a bottom plan of the same;

2

Figure 3 is a section along the line 3—3 of Figure 1;

Figure 4 is a section along the line 4—4 of Figure 1.

- 5 In the drawings, the magazine has an outlet portion 1, and internal longitudinal guiding ledges 2 formed in the walls thereof adjacent the lower boundary. The ledges 2 comprise rear portions 16 corresponding in shape to portions of the rear 10 of the cartridge 3, and arcuate inwardly extending projections 4 and 5 somewhat forward of midway longitudinally of the magazine, and adapted to engage on opposite sides thereof arcs of the case 10 of the cartridge 3.
- 15 The upper halves 12 of the projections 4, 5, extend longitudinally coincident with the projections, and the lower halves 14 merge with portions 16 of the ledges 2. The magazine interior wall has flat portions 15 above the portion 16, and 20 below the latter are the flat portions 17, which are inward of the portions 15.

- The ejection guide portions 11 connect the inner surfaces of the projections 4, 5, to the magazine wall forward of the projections. The 25 feed guide portions 13 connect the upper half portions 12 of the projections 4, 5, to the flat portion 15 of the magazine wall rearward of the projections.

- The distance 6 between the projections 4, 5, is 30 greater than the diameter 7 of the cartridge at the corresponding point longitudinally, and smaller than the greatest diameter 8 of the cartridge. The magazine is of resilient construction so that the rear portion of the cartridge, having 35 the greatest diameter 8, can drive the projections, 4, 5, apart and pass between them.

- In operation, a cartridge in the position shown 40 is driven forward by the breech block, not shown. As the cartridge diameter increases on a taper toward the rear, the projections 4, 5, will first engage the cartridge well in advance of the point of greatest diameter 8, which is greater than their own included distance 6. This engagement extends above and below the axis of the cartridge, 45 and keeps it pointed straight for the gun chamber, meanwhile braking or decelerating it. The cartridge is thus kept in steady engagement with the breech block which is advancing it, and cannot bounce ahead of the breech block and be fired 50 ahead of time. Of course, the resilient construction of the magazine permits the tapered cartridge to wedge apart the projections 4, 5, sufficient to permit passage of the cartridge. Since the breech block is properly engaging the cartridge, the extractor claw on the breech block is 55

also in proper engagement and will extract the cartridge when fired.

We claim:

1. An outlet portion for a firearm magazine, said outlet portion being constructed and arranged to accommodate tapered-case cartridges of a given caliber, and comprising resilient walls having formed therein guiding ledges, said ledges comprising a rear portion corresponding to portions of the rear portion of a cartridge, front portions on said ledges comprising inwardly extending projections each formed with an arcuate cartridge engaging surface extending above and below the axis of the cartridge, the included distance between said projections being smaller than the greatest diameter of a cartridge of said given caliber, whereby said projections are adapted to brake said cartridge in its forward travel and keep it in engagement with the breech block of the fire arm.

2. A magazine according to claim 1, said projections being two in number and located opposite each other.

3. An outlet for a firearm magazine, said outlet portion being constructed and arranged to accommodate tapered-case cartridges of a given caliber, and comprising resilient walls having formed therein guiding ledges, said ledges comprising rear portions corresponding to portions of

5

15

the rear portion of a cartridge, front portions on said ledges comprising a pair of oppositely disposed inwardly extending projections and constituting part of said guiding ledges each formed with an arcuate cartridge engaging surface, said projections comprising lower half portions merging with said ledges, and upper half portions, said upper half portions comprising portions connecting said upper half portions to flat wall portions of said magazine adjacent said guide ledges, the included distance between said projections being smaller than the greatest diameter of a cartridge of said given caliber.
